JOHN A. HOFF, OF ST. LOUIS, MISSOURI.

METHOD OF TESTING AERATED-BEVERAGE CONTAINERS.

1,272,043.

Specification of Letters Patent.

Patented July 9, 1918.

Application filed December 26, 1917. Serial No. 209,009.

To all whom it may concern:

Be it known that I, JOHN A. HOFF, a citizen of the United States, residing at St. Louis, State of Missouri, have invented certain new and useful Improvements in Methods of Testing Aerated-Beverage Containers, of which the following is a full, clear, and exact description, reference being had to the accompanying drawings, forming a part hereof.

The present invention is directed to improvements in methods of testing containers of aerated beverages or liquids charged with carbon-dioxide gas, the object of the test being to eliminate the danger of handling, and sending out to the trade and to the purchasing public containers which after once being filled with the liquid referred to, prove to be either too weak to resist the internal pressure of the gases, or so defective and leaky as to allow the gases to gradually escape. In the first case a bottle or container while being handled often ruptures and flies to pieces in the hands of the consumer or of the clerk serving a customer, the fragments cutting the hands of the person holding the bottle, and sometimes cutting the face and other exposed portions of the body. In the second case the gases being allowed to escape from the bottle leave the beverage flat and tasteless when the same is served. By therefore subjecting the bottles or containers to a proper test before they are delivered to the public, any and all bottles which can not endure the strain imposed thereon by the test are eliminated so that they never reach the consumer or the dealer. By my method of testing therefore, there is no possible way of a defective container or bottle leaving the manufacturer and consequently the public and the consumer can handle the bottles with proper safety as the probability of a bottle bursting or leaking under the pressure of the gases within is very remote. In practising my process I am not restricted to any particular form of apparatus. Many machines in fact are available; both manually operated and automatic. For purposes of illustration however, and by way of example, a manually operated machine is herein selected and I will therefore explain my invention in connection with such type of machine. The advantages of the invention will be fully apparent from the following detailed description in con-

nection with the accompanying drawings in which—

Figure 1 represents a vertical longitudinal section of one form of apparatus capable of carrying out my process, the plane of section being on the line 1—1 of Fig. 2, parts being in elevation; Fig. 2 is a top plan of the apparatus, the conveyers for the bottles being omitted; Fig. 3 is a vertical cross-section on the line 3—3 of Fig. 2, with parts in elevation; and Fig. 4 is an elevation of a modified form of apparatus for practising the invention.

Referring to the drawings, and for the present to Figs. 1 to 3 inclusive, 1, represents a tank or holder for water, (or other liquid) the same being supported by any suitable form of standard or frame 2 as shown. The top of the standard is formed with a centrally disposed depending cylinder 3 in which reciprocates a piston or plunger 4 secured to the upper end of the piston rod 5, the lower end of which carries a piston 6 operating in the cylinder 7. The piston 6 is operated hydraulically, the water circulating from the pipe 8 through the casing of the valve 9, pipes 10, and 11 leading from the valve casing to the cylinder 7 on opposite sides of the piston 6, and waste pipe 12 as well understood in the art. The cylinder 3 is in open and in free communication with the tank 1 through the bottom opening O of the tank, said opening being spanned by a wire gauze or reticulated sheet 13 resting on the tank bottom, said sheet forming the bottom of a suitable holder or tray 14 in which the bottles (or other containers) B containing the gas-charged beverage are deposited and with which they are inserted into the tank preparatory to the testing operation. The upper end of the tank 1 is surrounded by a trough or gutter 15 provided with a bottom packing ring or gasket 16, the outer wall of the trough being tapped by a pipe 17 leading from the casing of a "cracked" valve 18 (a valve left partly unseated so that a permanent flow of water may be had through the pipe 17) which is coupled to a pipe 19 leading from any suitable source of water supply. The overflow from the trough is by way of a recess r formed in the outer wall of the trough at a point diametrically opposite the pipe 17, a suitable overflow-lip 20 leading from the bottom of the recess and discharging 110

into a pocket 21 from the bottom of which leads a waste-pipe 22 which conducts the water to any desired point. Extending from one of the sides of the trough 15 and 5 spaced apart are bracket arms 23, the outer ends of which support a rock-shaft 24 to the ends of which are secured the hinge-arms 25 whose inner ends carry the outer frame 26 of the glass lid or door 27, the 10 side of the lid frame opposite the hinge arms 25 being provided with a handle 28. The hinge-arms 25 are formed with outer extensions 25' so proportioned and extended that when the lid is swung to open position 15 slightly past the vertical it will be arrested by the extensions or stops 25' striking the outer wall of the tank 1 (see dotted position of the lid in Fig. 3). When the lid is closed the outer free edge or flange of the frame 26 20 engages the gasket 16, the lid being clamped tightly to the gasket by the swing yokes 29 the arms whereof are pivotally secured to the bosses 30 at the bases of the side walls of the tank 1, the cross bar of each yoke being 25 provided with an operating handle 29' as shown. On the inner faces of the cross-bars of the yokes are preferably disposed cylindrical bars t which, when the yokes are swung to a clamping position, ride over the cam formations 26' of the frame 26 whereby the lid frame is gradually yet firmly forced into water-tight engagement 30 with the gasket 16.

Leading from the ring or fitting 31 at the 35 center of the glass lid 27 is a relief pipe 32 normally closed by a ball valve 33 confined in the casing 34, the casing being formed with a port or by-pass a connecting the pipe 32 (below the valve) with a vacuum 40 gage 35 to which atmospheric air may be admitted by a valve 36 in the pipe 37 leading from the T 38 by which the gage is coupled to the valve casing 34. Leading from the valve casing 34 across the lid 27 45 is an overflow pipe 39 terminating at its free end in an elbow 40 which, for a closed position of the lid, discharges into the waste pocket 21. Disposed on one side of the machine is an endless conveyer 41 traveling over suitable guides or tracks 42, the said conveyer being provided with hooks 43 for engaging the loops or handles h of the bottle holders or trays 14 as the latter are conveyed to the operator, a similar conveyer 50 41' with hooks 43', traveling over tracks 42' being disposed on the opposite side of the machine for conducting away the trays containing the tested bottles.

The operation will now be obvious from 60 the foregoing description, and briefly stated is substantially as follows: The tank 1 is first filled with water, the piston 4 being of course raised to bring its upper surface in the plane of the bottom of the tank, and the lid 27 swung to open position, the members

25' holding the lid substantially at the angle shown by the dotted position of the lid in Fig. 3. The operator thereupon detaches from the conveyer 41 a tray of bottles and deposits them into the tank and then closes 70 the lid clamping it tightly against the gasket 16 by the yokes 29 as shown in the drawings. The tank is thus practically full of water and the bottles are submerged 75 therein. The valve 36 being closed, the operator now turns the valve 9 to proper position to admit hydraulic water above the piston 6 (Fig. 1) causing the piston 4 to descend or move through a space just sufficient to overcome the atmospheric pressure 80 on the under side thereof and thereby relieving the bottles within the tank from the support of the normal atmospheric pressure 85 in said tank. In other words the bottles are now exposed to an extraneous pressure below normal atmospheric, and in the event that all the joints of the apparatus are airtight and the tank absolutely full of water at the beginning of the downward movement 90 of the piston 4, this pressure is practically reduced to a vacuum, so that the interiors 95 of the bottles are now in effect subjected to an absolute pressure of the gases within, that is to say, to the original pressure of the gases in the bottles plus the vacuum or reduced pressure without, depending on the degree of rarefaction resulting from the slight downward movement of the piston 4 as above described. Under these circumstances the gases within the bottles are permitted to expand and exert their maximum pressure against the walls of the bottles, and any defective bottles or such as are not capable of resisting the increased pressure will burst or break and thus are prevented from 100 being sent out to the trade or purchasing public. Moreover, any leaky bottles may be readily detected by observing the bubbles 105 escaping through the surrounding liquid around the corks or crown seals thereof, and these likewise may be discarded and held back from the consumer. At the conclusion 110 of the test the valve 36 is opened to destroy the vacuum in the tank 1 and permit the lid 27 to be swung open, whereupon the operator removes the tray 14 and attaches it to the hooks 43' of the conveyer 41' which conveys the bottles to any convenient point. The moment the valve 36 is opened and the 115 vacuum in the tank 1 destroyed, then, since the piston 6 coupled to the piston 4 is under (hydraulic) pressure, both pistons will drop so as to bring the piston 4 to the position substantially as shown in Fig. 1. The surplus water under the lid will then drop 120 down into the cylinder 3 on top of the piston 4, bringing the level of the water in the tank low enough to enable the operator to seize the handles or loops h without immersing 125 his hands in the water. Any water lost 130

by splashing and evaporation is restored by the stream trickling past the valve 18 into the gutter or trough 15, the overflow being discharged over the lip 20 into the pocket 21 whence it runs out through the waste pipe 22. After depositing the next lot of bottles into the tank 1 and closing and clamping the lid as previously described, the piston 4 is restored to its original position or top of its upward stroke by proper manipulation of the valve 9, any surplus water under the lid escaping through the pipe 32 past the valve 33, through the casing 34 and pipe 39 to waste pocket 21. The test of the next lot of bottles may now be effected in the same manner as that of the preceding lot and so on indefinitely. The rarefaction or vacuum in the tank 1 permits the atmospheric air to hold the lid tightly to its gasket 16 whereby an air-tight joint is assured during the test.

I may of course employ various forms of testing apparatus, both manually operated and automatic, the foregoing being but a single example of the many which may be utilized for the purpose. A very simple modified form is shown in Fig. 4. In that case I provide a platform 50 suspended from a head 51 by means of suspension bolts 52, said platform serving to support a glass bell 53 in which is confined a bottle or equivalent aerated beverage container B. The head 51 is provided with ports e, d, c, to which lead respectively a water-pipe 54 (provided with a valve V), an air-vent pipe 55 (provided with an air cock D), and vacuum pipe 56 (provided with valve V') connecting with a vacuum chamber or tank (not shown). The bell 53 terminates in a neck n provided with passages or ports m, m', communicating respectively with the ports e, d, and c. The valve V' being closed, by opening the valve V on pipe 54 and air cock D on pipe 55, the bell may be filled with water so as to submerge the bottle B. By now closing the valve V and cock D and opening valve V', the vacuum to which the pipe 56 leads will at once be communicated to the bell 53, and the bottle B be subjected to a test under practically absolute pressure. If the bottle bursts it shows that it would have been dangerous to send it out to the trade. If it leaks, the leakage can be detected by the bubbles of gas rising through the water surrounding the bottle, whereupon this particular bottle is discarded. To remove the bottle the operator detaches the platform 50 which allows the bottle to drop through the bottom of the bell 53, the water of course being lost. The apparatus last described is intended more for isolated laboratory tests and would hardly be serviceable for testing large quantities of bottles. The two forms of apparatus described are sufficient to illustrate my improved method of testing con-

tainers of aerated beverages (and other liquids charged with gases under pressure), and since no claim to the apparatus is herein made, the description of the forms of apparatus illustrated is deemed sufficient to a clear understanding of the invention.

The test should of course be continued a sufficient time to give the internal gases of the containers ample opportunity to exert their full pressure against the inner walls of the container or bottle being tested. The vacuum around the container need not of course be affected by the water method here described, any dry method falling within the spirit of my invention. Of course the water or wet method is simple, and has the advantage that where the bottles are allowed to be submerged leaks may be readily detected by watching the air bubbles rising through the liquid. It may be stated in passing that the initial slight downward movement of the piston 4 resorted to, to bring about a vacuous condition within the tank 1 necessarily causes a withdrawal of a small portion of the water which obviously follows the piston in such movement, this small portion being of course restored to the tank when the piston finally is returned to its first and uppermost position. It may be further added that when the tank 1 is first filled with water for testing the first lot of bottles, the piston 4 is dropped to substantially the position shown in Fig. 1 so as to likewise fill the cylinder 3. The reason for this is that after the tray 14 with its bottles is deposited in the tank and the lid 27 is closed and clamped, there should be a surplus of water in the tank so as to completely fill the tank and drive out all the air with the raising of the piston 4 to its uppermost position. In thus rising, the piston expels all excess of water through the top of the lid into the pipe 39 and into the waste as already described. The subsequent slight downward movement of the piston 4 to bring about a vacuous condition in the tank is in the nature of moving from its position a section of the wall of the tank, the plunger 4 operating as a movable section of the tank wall.

Having described my invention what I claim is:

1. The method of testing containers of aerated liquids which consists in submerging the container in a body of liquid confined in a suitable tank or holder, and withdrawing a portion of the liquid body from its original confines to create a vacuum in the space originally occupied by the volume of the liquid thus withdrawn, whereby the container is subjected to a test under the absolute pressure of the contained gases.

2. The method of testing containers of aerated beverages which consists in submerging the container in a body of liquid confined in a suitable holder, withdrawing a

- portion of the liquid body from its original confinement to create a vacuum in the space originally occupied by the volume of liquid thus withdrawn, whereby the interior of 5 the container is subjected to the resulting difference between the inside and outside pressures, exposing the container to view while said pressure is being maintained whereby leaky containers may be detected.
10. 3. The method of testing containers of aerated liquids which consists in submerging the container in a body of water confined in a suitable holder, withdrawing a portion of the liquid body from its original 15 confinement to create a vacuum in the space originally occupied by the volume of the liquid thus withdrawn, whereby the container is tested under substantially absolute pressure of the contained gases, and finally 20 removing the vacuum.
4. The method of testing containers of aerated liquids which consists in exposing the containers to an extraneous pressure reduced below normal atmospheric pressure, 25 in the presence of a body of liquid in which the container is partly or wholly submerged.
5. The method of testing containers of

aerated liquids which consists in inclosing the container in a body of liquid confined by the walls of a suitable holder, then moving 30 outwardly a wall or section of a wall of such holder a sufficient distance to overcome the atmospheric pressure on the outer face of such wall or section, whereby a vacuous condition is established in the holder around the 35 container, and the latter subjected to a test under absolute pressure.

6. The method of testing containers of aerated liquids which consists in surrounding them with a body of liquid confined in a 40 vessel without access of atmospheric air, and imparting a slight outward movement to a wall of the vessel or portion thereof in contact with the liquid, whereby a vacuous condition is produced in the vessel and the 45 container subjected to a test under absolute pressure.

In testimony whereof I affix my signature in presence of two witnesses.

JOHN A. HOFF.
